LIQUID SAMPLING DEVICE

Oliver E. McClusky, Beaumont, Tex.

Application October 27, 1947, Serial No. 782,261

5 Claims. (Cl. 73—425.4)

This invention relates to devices for securing a sample of liquid in a tank from any desired depth. Devices of this character are often employed in the sampling of crude oil, and when so used are commonly designated as "oil thieves" or "tank thieves." The conventional thief consists essentially of a tube open at both ends so that the liquid may flow freely through the tube as the tube is lowered into the tank. A valve associated with the lower end of the tube is arranged for actuation by suitable trip mechanism, either manually or automatically operable, whereby the lower end of the tube can be closed at the desired depth, so that the sample of the fluid is entrapped in the tube and may be withdrawn for inspection and testing.

It is an object of the invention to provide a sampling device which is simple and inexpensive to construct, readily operable either mechanically or automatically, and easily adjusted to effect automatic sampling of the liquid at a predetermined depth.

It is a further object of the invention to provide a sampling device of the character described in which displacement of the valve to the tube closing position is facilitated and a tight fit between the valve and its seat at the lower end of the tube is ensured. Thus it is often necessary to take a sample of liquid from the bottom of the tank, at which point sludge, shale, and other solids are present, and these solids may interfere with closing and seating of the valve at the lower end of the tube. In the preferred form of the invention, therefore, the valve and associated elements are so formed that sludge and other solids are displaced by the valve as the latter moves toward the tube closing position, and the valve plate is wedged against its seat to insure effective sealing of the tube.

Further objects and features of the invention will be apparent from the following description taken in connection with the accompanying drawings, in which

Figures 1 and 2 are a front and a side elevation respectively of a device to which the invention is applied:

Figure 3 is a section on line 3-3 of Figure 1;

Figure 4 is a partial sectional view taken substantially on the line 4-4 of Figure 3, showing the valve in opened positions; and

Figure 5 is a view corresponding to Figure 4, showing the valve closed.

In order to facilitate an understanding of the principles of the invention, the preferred embodiment illustrated in the drawings is described in

5 detail herein. It will be appreciated, however, that no limitation of the invention is thereby intended, and that such modifications of the illustrated structure are contemplated as would normally occur to those skilled in the art to which the invention relates.

As in the conventional oil thief, my device consists essentially of an elongated container or sampling tube, preferably comprising an elongated cylinder of transparent plastic or vitreous material, initially open at both ends, a valve operable to seal the lower end of the tube, and trip mechanism for effecting displacement of the valve to close the lower end of the tube.

15 The sampling tube, shown at 8 in Figs. 1 and 2, is received at its upper end in an annular groove formed in the lower face of a plate 9; the lower end of the tube is similarly received in the upper face of a plate 10, the annular groove therein being shown at 12 in Figs. 4 and 5. A plurality of threaded support rods 15, disposed in spaced circumferential relation about the tube 8, serve to clamp the plates 9 and 10 against the upper and lower ends respectively of the tube 8, as hereinafter more fully explained, forming with the plates 9 and 10 a supporting frame for the tube. A bail handle 16 secured to plate 9 is adapted to receive a line for lowering the device into a liquid container or tank. A thermometer 19 for measuring the temperature of the liquid at the desired depth and a scale plate 20 to indicate the height of the sample in the tube are suitably secured to the device. The upper and lower plates 9 and 10 are provided with ports 17 and 18 respectively, so that liquid may move freely through the tube 8 as the device is lowered in a tank.

The valve mechanism for sealing the lower end of the tube may be secured to the plate 10 by the supporting rods 15, the latter extending through apertured ears in the plate 10 and being received in threaded apertures in corresponding ears formed on a valve body 23; lock nuts 25, threaded on the bolts 15, engage the apertured ears on the plate 10 and serve to prevent loosening of the bolts 15.

45 In its preferred form, the movable portion of the valve comprises a carrying member 32 and a closure member 33, the closure member being supported on the carrying member for rocking movement with respect thereto. For instance, the carrying member may be formed with a central projection 35 which is received within a conforming recess in the lower face of the closure member 33, so that the two members are maintained in spaced relation as shown more partic-
50
55

ularly in Figs. 4 and 5. The upper face of closure member 33 is arranged to seat against the lower face of plate 10, whereas the carrier member 32 is received with slight mechanical clearance in a longitudinal slot or opening 38 formed in the valve body 23. Thus as the member 32 is reciprocated in slot 38, the rocking connection between members 32 and 33 permits the latter to engage snugly with the lower face of the plate 10, so that when the parts occupy the position in which they are shown in Fig. 5, the port 18 in the plate 10 is effectively sealed.

In order that the valve may be freely displaced to tube closing position but will at the same time be pressed firmly on its seat, the bottom wall defining slot 38 is inclined upwardly in the direction in which the valve is moved to close the port 18, the inclination being somewhat exaggerated in Figs. 4 and 5 of the drawing. Thus as carrier member 32 is displaced toward the left from the position in which it is shown in Fig. 4, it is concurrently displaced slightly toward plate 10, so that in its extreme left-hand position, as shown in Fig. 5, it exerts a wedging action on the rocking valve member 35, to force the latter upwardly and firmly against its seat on plate 10, thus sealing the tube 8 and preventing discharge of its contents as the device is lifted from the tank. It will be noted that slot 38 is open at both ends, so that sludge or other solids entering the valve body are ejected from slot 38 as the valve moves into the closed position.

Valve body 23 is formed to provide a yoke portion 40 carrying a bearing plate 41 in which is slidably mounted a valve actuating rod 42, the latter being threaded or otherwise secured in the valve carrying member 32. A coil spring 44, surrounding the rod 42 and engaging at its ends with the bearing plate 41 and carrying member 32 respectively, urges the valve carrying member and the rod toward the valve closing position in which the parts are shown in Fig. 5. A knob 46 threaded on the end of rod 42 permits manual withdrawal of the valve to open the port 18 against the action of spring 44.

A valve trip rod 50 extends longitudinally of tube 8, and passes through aligned apertures in plate 10 and valve body 23, being slidable therein. A latch 52 is adjustably secured to rod 50 by set screw 53, the latch 52 and rod 50 being yieldably urged in a downward direction by a coil spring 54 surrounding the rod 50 and engaging at its ends with the latch 52 and a bracket 55, bracket 55 being apertured to receive rod 50 and being secured to an adjacent supporting rod 15 by set screw 56. The degree of compression of spring 54 may thus be adjusted by means of set screw 56, the bracket 55 being displaceable on its supporting rod 15 to the extent required. The position of latch 52 on valve trip rod 50 may be similarly adjusted by manipulating set screw 53, so that the extent to which trip rod 50 projects below the valve body 23 may be readily altered.

At its outer end, latch 52 is formed with a toe 58. As the valve carrying member 32 and valve actuating rod 42 are displaced to the left, or toward valve opening position, the toe 58 of the latch is engaged and lifted by the inclined face 59 on the valve carrying member 32 and drops behind a shoulder 60 thereon, to retain the valve carrying member in its extreme left-hand position (Fig. 4) against the action of spring 44. Thus the device may be initially set with the valve open by manually displacing rod 42 and

the valve elements, the latch 52 serving to retain these parts in that position. When the valve trip rod 50 is lifted, either by operation of a line secured to its upper end, or when the lower end of the rod strikes the tank bottom, the latch 52 is lifted to release the valve elements, which are then displaced to the left from the position of Fig. 4 by the spring 44, thereby sealing the port 18 with a wedging action as shown in Fig. 5. Nuts 62 may be threaded on an adjacent support rod 15 to afford an abutment for engagement by latch 52, whereby upward movement of the latter is limited.

The mode of operation of the device will be apparent from the foregoing description. The valve is initially set in the open position by manual displacement of the rod 42, and the associated valve parts, the latter being locked in the displaced position by latch 52. The device is lowered in the liquid container or tank, and since both ends of the tube 8 are open, the liquid will pass freely through the tube, which therefore contains at any instant a sample of the liquid at the level to which the device has been lowered. If the sample is to be taken at a point elevated considerably above the bottom of the tank, the trip rod 50 is displaced upwardly by an operating line attached thereto, thus releasing the valve parts and allowing them to move to the left to effectively seal the lower end of the tube 8, which is then withdrawn from the tank. If a sample from adjacent the bottom of the tank is desired, the trip rod 50 is appropriately positioned on the device by adjusting set screws 53, 56, so that the rod projects below the bottom of the device to the desired extent. On engaging the bottom of the tank, the trip rod is displaced upwardly to effect automatic release and closure of the valve. To facilitate setting of the trip rod 50 for such automatic operation, the trip rod may be provided with indicia affording a visual indication of the setting of the rod, whereby the valve may readily be automatically closed at the desired level above the tank bottom.

Having thus described the invention, what is claimed as new and desired to be secured by Letters Patent is:

1. In a liquid sampling device, the combination with an elongated open ended container adapted to be lowered into a tank of liquid to be sampled, of valve means for closing one end of said container on immersion of the latter in the liquid to a predetermined depth, said valve means comprising a valve body secured to said container and having a port communicating with the container end, said valve body being formed to provide a slot extending transversely of the axis of the port, said slot being open at both ends, a valve carrier supported for displacement in and lengthwise of said slot, a valve plate pivotally supported on said carrier for rocking movement with respect thereto, said valve plate being movable lengthwise with said carrier into port closing position, the base of said slot being inclined toward said port in the direction of port closing movement of said carrier, whereby said plate is wedged against said port as said carrier is so moved, spring means for urging said carrier toward port closing position, and releasable latch mechanism for retaining said carrier in port opened position.

2. In a liquid sampling device, the combination with an elongated open ended container adapted to be lowered into a tank of liquid to be sampled, of valve means for closing one end of said con-

tainer on immersion of the latter in the liquid to a predetermined depth, said valve means comprising a valve body secured to said container and having a port communicating with the container end, said valve body being formed to provide valve guide means extending transversely of the axis of the port, a valve carrier supported for displacement in and lengthwise of said guide means, a valve plate supported on said carrier for rocking movement with respect thereto, said valve plate being movable lengthwise with said carrier into port closing position, said guide means being inclined toward said port in the direction of port closing movement of said carrier, whereby said plate is wedged against said port as said carrier is so moved, spring means for urging said carrier toward port closing position, and releasable latch mechanism for retaining said carrier in port opened position.

3. In a liquid sampling device, the combination with an elongated open ended container adapted to be lowered into a tank of liquid to be sampled, of valve means for closing one end of said container on immersion of the latter in the liquid to a predetermined depth, said valve means comprising a valve body secured to said container and having a port communicating with the container end, a valve carrier supported for displacement on said valve body transversely of said port, a valve plate pivotally supported on said carrier for rocking movement with respect thereto, said valve plate being movable lengthwise with said carrier into port closing position, means acting between said carrier and said valve body to wedge said plate against said port as said carrier is so moved, and means for displacing said carrier toward port closing position.

4. In a liquid sampling device, the combination with an elongated open ended container adapted to be lowered into a tank of liquid to be sampled, of valve means for closing one end of said container on immersion of the latter in the liquid to a predetermined depth, said valve means comprising a valve body secured to said container and having a port communicating with the container end, said valve body being formed to provide valve guide means extending transversely of the axis of the port, a valve carrier supported for displacement in and lengthwise of said guide means, a valve plate supported on said carrier for rocking movement with respect thereto, said valve plate being movable lengthwise with

9 said carrier into port closing position, said guide means being inclined toward said port in the direction of port closing movement of said carrier, whereby said plate is wedged against said port as said carrier is so moved, spring means for urging said carrier toward port closing position, a latch rod supported on said device for displacement lengthwise of said container, said rod projecting below said device for engagement with the tank bottom, a latch for engaging and retaining said valve carrier in port opened position, and means adjustably securing said latch to said rod.

15 5. Valve means for use in a liquid sampling device having an elongated open ended container adapted to be lowered into a tank of liquid to be sampled, said valve means serving to close one end of said container on immersion of the latter in the liquid to a predetermined depth, said valve
20 means comprising a valve body secured to said container and having a port communicating with the container end, said valve body being formed to provide a slot extending transversely of the axis of the port, said slot being open at both
25 ends, a valve carrier supported for displacement in and lengthwise of said slot, a valve plate pivotally supported on said carrier for rocking movement with respect thereto, said valve plate being movable lengthwise with said carrier into port
30 closing position, the base of said slot being inclined toward said port in the direction of port closing movement of said carrier, whereby said plate is wedged against said port as said carrier is so moved, spring means for urging said carrier toward port closing position, and releasable latch mechanism for retaining said carrier in port
35 opened position.
